STEPHEN J. BURTON, OF CHARLESTOWN, ASSIGNOR TO AMERICAN STEAM FIRE-PROOF-SAFE COMPANY, OF BOSTON, MASSACHUSETTS.

Letters Patent No. 103,841, dated June 7, 1870.

IMPROVEMENT IN BOLTING DEVICES FOR SAFES.

Schedule referred to in these Letters Patent and making part of the same

To all persons to whom these presents may come:

Be it known that I, STEPHEN J. BURTON, of Charlestown, of the county of Middlesex and State of Massachusetts, have invented a new and useful Improvement in Locks, or the Bolting Mechanism for a Safe; and I do hereby declare the same to be fully described in the following specification, and represented in the accompanying drawing, of which—

Figure 1 denotes a side elevation of a permutation lock, and the bolts of a safe-door, with my invention applied thereto.

Figure 2 is a side view of the bolt-actuator, and the weighted tri-armed lever to be hereinafter described.

In the drawing—

A denotes the bolt-supporting case or frame, and B B', two bolts arranged so as to slide longitudinally in such frame, such bolts being connected to each other by a vertical plate, C, extending from one to the other of them.

The actuator for throwing or moving the bolts is represented at D, as fixed on the end of the spindle a, of a knob.

This actuator has one or more notches, b c, made in its periphery, and it is to operate with a tri-armed lever, E, whose fulcrum d, projects from the plate C.

An inner side view of such plate and lever is exhibited in Figure 3, in which there is represented not only an over-balance weight, e, fixed to the shortest arm of the lever, but a tooth, f, extended down from such arm, and between two stops or studs g h, projecting from the plate C, the whole being as shown in the drawing.

The upright or lowermost arm i, of the lever, has a stud, k, extended from its lower part.

Furthermore, there is an abutment, l, fixed to the bolt-case, and arranged with respect to the lever E in manner as shown in fig. 1.

A permutation lock, H, is employed to raise and lower or operate an arm, I, which turns upon a center or pivot, K. This arm may be considered as the bolt of such a lock.

A hook, L, pivoted to the arm, constitutes a part of the lock, and is operated by the cammed disk M thereof.

The range of motion of the arm I is between and detained by the ends of a slot or notch, O, formed in the lock-case P, one extreme position of the arm being indicated in the full black lines, and the other in dotted lines in fig. 1.

From the above, it will be seen that the rotary bolt-actuator D, is separated and isolated in action from the permutation wheels or plates of the lock, one of such wheels being shown at m.

This actuator, however, is not so arranged that any

inward pressure upon the bolt will be exerted on the bearing of the said actuator, and have no action or effect upon the said permutation wheels.

In my bolting-mechanism, the bolt actuator can revolve without producing any movement of the bolts, so long as the actuator may be out of engagement with the tooth f of the tri-armed lever. When the actuator is in engagement with such tooth f, the rear arm of the said lever will be raised above the abutment l.

While the arm I is elevated to its highest position, the tri-armed lever will be free to be moved by its weight, which will operate the said lever or turn it on its pivot in such a manner as to cause the tooth f to pass into one of the notches of the actuator, while the actuator may be in the act of being revolved. The tooth, by such notch, during the continued rotary movement of the actuator, will be forced against one of the studs g h, and thus so engage the actuator with the plate C as to cause it and the bolts to be removed during the continued movement of the actuator.

As soon as the bolts may have been advanced by the actuator to the extent of their forward movement, the tri-armed lever will have been carried beyond the abutment, and by the actuator will be turned down directly in front of the abutment, and so long as such lever is in such position with respect to the abutment, the two will prevent the bolt from being shot or moved backward or retracted.

The purpose of the lock is to retain the tri-armed lever in this position, leaving the actuator out of engagement with the tooth of the lever, and free to be revolved without effecting any movement of the bolts, and this the lock will do when the arm I is depressed to its lowest position, as under such circumstances the arm will rest on the stud k of such lever, and as a consequence while in such a situation, it will prevent any movement of such lever. When the arm is in this position it may be said to be "locked," but when in its other position it may be said to be "unlocked."

Now, when the arm is locked, its operative hook will be elevated upon the periphery of the cammed disk, and up in front of an abutment, p, extended from the lock-case, as shown in fig. 1.

By operating the lock so as to elevate the arm I to its highest position, the weight of the tri-armed lever will be free to act in a manner to cause the lever to be engaged with the actuator. By revolving the actuator the engagement may be effected, the tri-armed lever be raised above the abutment l, and the bolts be forced back, the tri-armed lever in the mean time moving over the top of the said abutment l.

Locks of various other kinds will suffice to hold the

tri-armed lever down in its lowest position, it only being necessary to so arrange the bolt of any such a lock relatively to the stud of the lower arm of such lever, that, when such stud is in its lowest position, and the bolt is shot forward, the latter may extend upon and lock or hold the stud in place.

I employ a permutation lock, and a rotary arm, I, as described, as a very efficient means of locking the tri-armed lever.

The lock is so insulated from the bolting-mechanism, that any back pressure applied directly to either of the bolts can in no respect affect the lock or any of its parts, and especially the wheels, when the lock used is a "permutation lock."

In case the weight of the tri-armed lever may not be deemed sufficient, a spring may be substituted to operate the lever. In order to insure the correct operation of such lever, that is, so as to cause its teeth to engage with the actuator at the proper time, there may be a stud projected from the tri-armed lever, and arranged in such a manner as to be struck by the arm I while being elevated, the whole being so as to effect the proper movement of the lever by the said arm.

The advantages of my invention may be thus stated:

It enables the main bolts to be removed any required distance, without regard to the throw of the lock-bolt. It completely insulates the main bolt-act-

uator from the bolts and the lock, thereby preventing the main bolts from being moved by the actuator when the tri-armed lever is locked.

I am aware that by means of a lock, a gear revolving loosely on the spindle of a knob, and engaged with a rack applied to a bolt, has been clutched to the spindle so as to be revolved therewith, in order to effect a throw or movement of the said bolt, a clutch to be actuated by the lock being applied to the spindle.

I make no claim to this, for, with my apparatus, the lock performs no function of operating a clutch for the purpose as mentioned, but simply answers the purpose of locking the tri-armed lever.

I make no claim to any part or combination described in the United States patent, No. 57,574.

What I do claim as my invention, may be thus defined:

The arrangement and combination of the rotary arm I, with the permutation lock provided with the hook, as set forth, such arm being to operate with the tri-armed lever in manner as described, when such lever is applied to and used with the bolt or bolts and the actuator, as explained.

STEPHEN J. BURTON.
